(57) **CLAIM**

We claim, the ornamental design for a display screen or portion thereof with animated graphical user interface, as shown and described.

DESCRIPTION

FIG. 1 is a first image in a sequence for a display screen or portion thereof with animated graphical user interface showing our new design in a first embodiment;

FIG. 2 is a second image in a sequence thereof;

FIG. 3 is a third image in a sequence thereof;

FIG. 4 is a fourth image in a sequence thereof;

FIG. 5 is a fifth image in a sequence thereof;

FIG. 6 is a sixth image in a sequence thereof;

FIG. 7 is a seventh image in a sequence thereof;

FIG. 8 is an eighth image in a sequence thereof;

FIG. 9 is a ninth image in a sequence thereof;

FIG. 10 is a tenth image in a sequence thereof;

FIG. 11 is an eleventh image in a sequence thereof;

FIG. 12 is a first image in a sequence for a display screen or portion thereof with animated graphical user interface showing our new design in a second embodiment;

FIG. 13 is a second image in a sequence thereof;

FIG. 14 is a third image in a sequence thereof;

FIG. 15 is a fourth image in a sequence thereof;

FIG. 16 is a fifth image in a sequence thereof;

(Continued)

FIG. 17 is a sixth image in a sequence thereof;
FIG. 18 is a seventh image in a sequence thereof;
FIG. 19 is an eighth image in a sequence thereof;
FIG. 20 is a ninth image in a sequence thereof;
FIG. 21 is a tenth image in a sequence thereof; and,
FIG. 22 is an eleventh image in a sequence thereof.
The broken lines showing the display screen or portion
thereof are for the purpose of illustrating environmental
structure and form no part of the claimed design.
The appearance of the transitional image sequentially transi-
tions between the images shown in FIGS. 1-11 and 12-22.
